NEUTRAL-TO-POLAR CURRENT CONVERSION CIRCUITS

James Stallings Harris, Old Greenwich, Conn., assignor to Radio Corporation of America, a corporation of Delaware

Application April 29, 1952, Serial No. 284,863

8 Claims. (Cl. 178—70)

The invention relates to telegraph signalling circuits. It particularly pertains to circuit arrangements for converting signal currents appearing in neutral form into signal currents of polar form.

Fundamentally in any telegraph signalling circuit intelligence is transferred by means of switching the transmission line input terminals to effect a change in the current conditions of the circuit. A familiar example of such a circuit is a D.-C. telegraph circuit employing printing telegraph equipment in which the signal is actually detected by a magnetically operated armature in the receiving printer. In order for the receiving equipment to properly interpret the intelligence transmitted, it is essential that the position of the armature of the receiving printer accurately follow the keying device at the remote transmitter. That is to say, that the duration between transitions of the armature should be the same as the duration between transitions of the contacts of the keyer. Assuming that the wave filter characteristics of the transmission line are satisfactory, the adjustment of the circuit which will satisfy the requirement as mentioned above is largely a matter of adjusting the power supply voltage and total circuit resistance to provide a specified current in the armature coil during steady-state "marking" condition. In usual practice the power supply voltage is fixed so the adjustment is actually an adjustment of resistance in the circuit. Because the transmission line impedance is usually fixed, such adjustment may be made only at the ends of the transmission line.

As is well known to those familiar with the telegraph art, such a circuit works satisfactorily only so long as the transmission line impedance actually is a fixed quantity, and any changes in this impedance requires compensation at one or both of the terminal ends of the line if operating tolerances are to be maintained.

In the case of long transmission lines the current at the load end of the circuit will vary due to changes in both humidity and temperature. Such changes do occur relatively slowly as compared with the speed of changes due to the intelligence keying impressed upon the line, but the circuits require periodic readjustment to maintain adequate tolerances.

In order to eliminate the requirement for these readjustments due to changes in line characteristics, which may be considered as changes in line attenuation, it is almost universal practice to use a different circuit on long lines. This circuit is known as the two-current or "polar circuit."

In the two-current circuit the "mark" and "space" currents are identical in magnitude but opposite in polarity. Changes in line attenuation, therefore, affect the magnitudes of the "mark" and "space" currents to the same degree, but have no effect on the polarity component. The prior art signal detection device in such circuits may be, and usually is, a simple polar relay which responds to a combination of current magnitude and polarity, the response being effected at a current magnitude determined by the physical characteristics of the particular relay.

2

In a properly operating circuit, the magnitude of current required for proper operation of the relay in either direction is usually the same. With such a signal detection device it is only necessary to assure that under the maximum anticipated line attenuation the current supplied to the device will not exceed the safe maximum which may be applied to the device without damage or malfunction.

There are a large number of existing neutral signal type lines however that do not lend themselves for polar operation and which would require extensive alterations in order to convert them for polar operation. Obviously such alterations are expensive from both pecuniary and circuit time standpoints.

15 It is an object of the invention to convert neutral or "single" signalling current to a form approximating the performance of polar or "two" signalling currents in an improved manner.

It is another object of the invention to provide an improved control circuit arrangement for converting neutral or "single current" signals to polar or "two current" signals.

A further object of the invention is to provide an improved tone signal converter and monitoring circuit 25 adaptable for use in a multiplex receiving installation and including a control circuit arrangement for converting neutral or "single current" signals to polar or "two current" signals.

The objects of the invention are attained in a circuit 30 arrangement comprising three resistive elements, a capacitive element and a switching element. One of the resistive elements is arranged between the neutral signal input terminals. The other resistive elements are connected in series across the capacitive element to form a potential storing and dividing network which is connected in series with the switching element across the input terminals. The series arrangement between the junction of the series connected resistive elements and the switching element is connected to the output terminals of the novel circuit arrangement. In accordance with the basic principles of the invention the switching element is arranged to close when, and only when, the signal voltage across the input terminals equals or attempts to exceed the voltage across the capacitive element.

40 A current conversion circuit according to the invention may be used to operate a polar relay directly or through the intermediary of an electronic amplifier. Alternately a differential amplifier may be driven by the current conversion circuit to operate any desired utilization device.

50 Another mode of operation may employ a conversion circuit according to the invention for triggering a nonstable or a bistable reciproductive circuit, sometimes respectively referred to as flip-flop and locking circuits.

By changing the relative values of the series connected 55 resistive elements "zero current space-current mark" signals, "proportional current mark-space" signals, and "double current" or opposite polarity mark-space signals may be accommodated. Such changes can also be made for the purpose of reducing distortion present in a received signal or conversely for the purpose of introducing a desired distortion or "weighting" of the signal.

The invention will be illustrated in connection with specific embodiments thereof given by way of example only and described with reference to the accompanying 60 drawing forming a part of the specification and in which:

Figs. 1 and 2 are diagrammatic representations of telegraph signalling circuits known to the art;

Fig. 3 is a schematic diagram of a circuit arrangement 70 basic to the invention;

Figs. 4 and 5 are functional diagrams useful in ex-

plaining the operation of the circuit arrangement shown in Figs. 3;

Figs. 6-10 are schematic diagrams of alternate embodiments of the circuit arrangement according to the invention; and

Fig. 11 is a schematic diagram of a tone signal converter and monitoring circuit incorporating the current conversion circuit of the invention.

Referring to Fig. 1, there is shown an equivalent circuit diagram of a known single-current electric signalling circuit comprising a transmission line 15 to which a signal detection device 17 and the equivalent load impedance 19 are connected. Intelligence is transferred to the detection device 17 located at the receiver by means of a keying device 21 located at the transmitter which switches the input terminals of the transmission line 15 to effect a change in the current conditions of the circuit. A current source 23 and the equivalent "mark" source impedance 25 are connected to the line 15 by the keying device 21. It is obvious that the corresponding "space" source impedance 27 may be equivalent to an open circuit in which case the keying device 21 may consist of only two contacts in a "make-and-break" circuit. In order for the receiving equipment to properly interpret the intelligence transmitted, it is essential that the signal detection device accurately follow the movable contacts of the keying device 21. That is to say that the duration between transitions of the armature at a telegraph printer, for example, should be the same as the duration between transitions of the contact of the keying device 21. Assuming that the wave filter characteristics of the transmission line 15 are satisfactory, the adjustment of the circuit which satisfies the requirement as mentioned above is largely a matter of adjusting the voltage of the source 23 and total circuit resistance to provide a specified current through the detection device 17 and the load impedance 19 during steady-state "marking" condition. In usual practice the source voltage is fixed so that in practice the adjustment is actually an adjustment of resistance in the circuit and is made only at the ends of the transmission line.

Such a circuit will be satisfactory as long as the transmission line impedance actually is a fixed quantity. Any changes in this impedance require compensation at one or both of the terminals in order to maintain the operating tolerances.

In the case of long transmission lines, the two-current or "polar circuit" shown in Fig. 2 is employed at the transmitter, the remainder of the circuit being as shown in Fig. 1.

In this type of circuit the "mark" and "space" currents obtained from the sources 23 and 29 are usually identical in magnitude but opposite in polarity and the source impedances 25 and 27 are likewise identical so that changes in line attenuation affect the magnitudes of the "mark" and "space" currents to the same degree.

The double-current circuit is also valuable under conditions where the signal as received may include extraneous noise or interference components of a magnitude sufficient to cause false operation of a single current device, as they can be made ineffective in a two-current circuit provided they are within the limitations of allowable maximum current.

The preceding information, repeated here only for background purposes, is well known and more complete discussions may be found in the literature of the communications art.

Further, while the preceding discussion has assumed a continuous D.-C. circuit between the keying device at the transmitter and the signal detection device at the receiver, it is to be understood that the circuit theory of the embodiment to be described is not affected if carrier methods are employed on the transmission line 15 with the understanding that the actual signal applied at

the final utilization point (for example, the printer magnet) is usually a single current signal, and that single frequency "on-off" A.-C. or "keyed tone" signals on the transmission line correspond to "single current" circuitry, while "two frequency" or "frequency shift" signals on the transmission line correspond to "two-current" or "polar" circuitry. It should also be recognized that where the transmission line includes a radio circuit the changes in line attenuation may be quite rapid.

Referring to Fig. 3 there is shown in schematic form a basic circuit arrangement according to the invention, comprising neutral signal input terminals 31-32, a resistive element R3, a shunt network 35, a switching element S and polar output terminals 37-38. The resistance element R3 may be an actual resistor or may be found in a resistive path of the circuit to which the input terminals 31-32 are connected. The shunt network 35 comprises a capacitor C and two resistance elements R1 and R2 connected in series across the capacitor C. The resistance elements R1 and R2 may be separate resistors, a single tapped resistor or a potentiometer having a variable tapping arm. The switching elements may be any known device will present a very low impedance at the operating frequency between the lower end of the shunt network 35 and the terminals 32 and 38. In accordance with the invention, the switching elements should close when, and only when, the potential applied across the input terminals 31-32 equals or attempts to exceed the voltage across the network capacitor C. This feature will be discussed further as the description progresses.

The circuit supplying power to the neutral input terminals 31-32 should preferably be relatively low in impedance as compared to the sum of resistances of the network resistors R1 and R2 and should also preferably supply current—and voltage—during the "idle" condition. That is, "mark" is the steady state idle condition, while the "space" or no current condition appears during keying. The time constant of the network comprising the capacitor C and the resistors R1, R2 should be long with respect to the anticipated maximum continuous spacing interval.

Under these conditions, the schematic representation of Figs. 4 and 5 illustrate the manner in which the circuit functions. The capacitor C is charged to the steady state "mark" voltage E_m through the switching element S and the relatively low effective resistance of the source resistor R_s and the resistance element R3, while the discharge path is the series connection of the resistors R1 and R2. In the "space" condition the resistance element R3 serves to reduce the potential between the neutral input terminals 31-32 to zero when the current source 18 is removed. As shown in the two Figs. 4 and 5, the output voltages for the two conditions are as follows:

$$\begin{array}{ll} \text{Input} & \text{Output} \\ \text{Mark} = E, \text{ Volts} & E \cdot \frac{R_2}{R_1 + R_2} \\ \text{Space} = \text{Zero Volts} & -E \cdot \frac{R_1}{R_1 + R_2} \end{array}$$

Thus the voltage between the output terminals 37-38 reverses in polarity for the two conditions. The total magnitude of change in the output voltage is equal to the magnitude of the input voltage under "mark" condition, and the relative magnitude of the "mark" and "space" voltages is determined by the relative resistances of the two resistors R1 and R2. Thus if the resistance values of the resistors R1 and R2 are equal, the output voltage will be a balanced polar voltage, while if the values are unequal, the output will be an unbalanced polar voltage with the degree of voltage unbalance equal to the degree of resistance unbalance.

While the actual transmission line between terminals still remains a neutral signal line, the circuit arrange-

ment according to the invention provides the equivalent of an entirely polar signal line within practical tolerances. This is so because the polar signal detector device is affected only by differences in polarity and not by differences in amplitude of the keyed signal.

The switching element S has been shown to be required to be closed when the voltage across the neutral input terminals 31-32 equals the voltage across the capacitor C, and open when the capacitor voltage exceeds the input voltage. A fast operating relay connected across the input terminals 31-32 could be used to approximately satisfy this requirement, while a unilateral impedance element such as a diode, vacuum or otherwise, with a high back-resistance, makes an almost ideal electronic switch. A multi-element switching tube could also be used if desirable, of course. For example, a triode tube might be used in a multiplex circuit where a plurality of such triodes were triggered in succession or determined by the timing device of a time division multiplex system.

A practical signal repeating circuit can be made using the basic neutral-to-polar circuitry of Fig. 3 with a diode switch 61 and with a sensitive polar relay 63 as an amplitude selection device as shown in Fig. 6.

In this circuit, it is obvious that during "spacing" condition the operating power for the polar relay 63 is supplied from the energy stored in the capacitor C. In some cases this requirement for energy supply will make the desirable ratio between charging and discharging time constants of the shunt circuit 35 difficult to obtain, and in such cases the use of an electronic circuit, which requires little or no energy from the conversion circuit, but functions on voltage differences, is indicated. This electronic circuit may in turn drive an electro-mechanical polar relay, or alternatively, with any required D.-C. power amplification, may drive a single current relay, or the final utilization device.

The electronic circuit may be in the form of the well known "differential-amplifier" circuit, or it may be of the "bistable reciproconductive" circuit form.

As employed herein, the term "reciproconductive circuit" is construed to include all two-tube regenerative devices in which conduction alternates in one or the other tube in response to applied triggering potential. The term "multivibrator" is sometimes applied to this circuit and the term "locking circuit" is sometimes applied to the bistable reciproconductive circuit in which two triggers are required to switch from one stable state to the other and return.

In certain instances it may be a single-ended stabilized circuit such as is commonly used in vacuum tube voltmeter circuits. Two separate stabilized single-ended amplifiers may be employed in connection with polar relays, either electro-mechanical or electronic, with one amplifier connected to one winding of the polar relay to provide "bias" or "correction" voltage and the other amplifier connected to the other winding to provide "signal" voltage.

The basic circuit may be used where the source "two-condition" signal is zero current for "space" and current for "mark" as outlined in the explanation of the basic circuit of Fig. 3, with the resistances of the resistors R1 and R2 equal (or replaced by a center tapped single resistor) to convert the neutral signal to a balanced polar signal and thus accurately repeat the transmitted signal without regard to the absolute magnitude of the "mark" current, within, of course, the operating limit of the circuit.

The basic circuit also may be used where the "space" condition is not zero but of the same polarity and is proportional to the mark signal by making the resistances of the resistors of R1 and R2 proportional to the sum and difference ratios of "mark" and "space" signals, and this signal will be converted to a balanced polar signal.

It may be used where the "space" condition is not zero but is of opposite polarity and fractionally proportional to the "mark" signal by making the resistances of the resistors R2 and R1 proportional to the sum and difference ratios of the "mark" and "space" signals, and this signal will be converted to a balanced polar signal.

In any of the previous instances, if it is desired to repeat the signal with an added characteristic distortion, or to eliminate a characteristic distortion from the original signal by introducing an equal but opposite characteristic distortion, this may be accomplished by changing the resistance proportions of the resistors R1 and R2. If an appropriate signal delay network, for example, the source and transmission line impedance, is introduced in the circuit ahead of the conversion circuit, and the tap between the resistors R1 and R2 is made variable by using a potentiometer type of resistor with or without series fixed resistors, then the characteristic distortion introduced may be varied at will and calibrated if desired.

While the basic neutral-to-polar circuit is shown as a metallic circuit, with no reference to ground, it is to be clearly understood that the circuit may be a single-wire and ground return circuit or may have a ground connection (or ground reference connection) to either end of the power source.

Further, the switching element S may be connected to either the grounded or ungrounded leg of the transmission line, and either polarity of the source 18 may be grounded, provided any diode or multi-element tube used as the switch S is properly polarized.

In the basic circuit the operating range, or the signal level variation, over which the circuit will function is limited at one extreme by the minimum sensitivity of the devices or circuits following the neutral-to-polar circuit, and at the other extreme by the maximum allowable, practicable or desirable signal available. If in practice it is desirable to provide a minimum sensitivity below which the signal output will assuredly be "space" then a minimum biasing voltage arrangement may be inserted in the neutral-to-polar conversion circuit as shown by way of example only as a battery 71 in Fig. 7. This arrangement will not cause any distortion to a signal that exceeds the bias voltage of the battery 71.

If a diode employing a hot cathode or other hot cathode multi-element tube is employed as the switch and the effects of contact potential cause undesirable output signal distortion at minimum operable signal input levels, the effects may be eliminated or minimized by interposing a source of corrective voltage as shown by way of example as a battery 81 in Fig. 8. Compensation for both contact potential and establishment of minimum signal bias may be combined, as shown by way of example by batteries 81 and 71 in Fig. 9. It is to be understood, of course, that any source of potential such as a generator, an A.-C. rectifier or the like may be substituted for the batteries shown.

In a D.-C. or on-off single tone frequency A.-C. circuit employing more than two conditions, with each condition or combination of conditions providing different items of information, and where each condition bears a definite proportional relationship to the maximum "mark" and "space" conditions, a multiplicity of the circuits according to the invention may be employed at the load end of the transmission line with appropriate cross connections and/or couplings to reproduce the information transmitted.

In a circuit utilizing frequency shift A.-C. as the signal carrier over the transmission line and where due to practical conditions the absolute magnitude and/or polarity of the demodulated signal cannot be utilized to determine the intelligence being transmitted but where the limits of amplitude of excursion can be established according to the invention, the neutral-to-polar conversion circuit may be adapted to definitely interpret the information.

In a system employing a multiplicity of signal sources and/or loads with standardized impedance and/or attenuation characteristics, and with associated transmission lines which may have different and/or varying characteristics, and where cross connections may be established between any pair of signal sources and loads through available transmission lines, the use of the circuits described allows connection changes without the requirement of readjustment of sources or loads when such changes introduce a change in transmission line characteristics.

Where the basic circuit, such as is shown in Fig. 3, is followed by a bistable reciproconductive or "locking circuit" and reversals are not being received during idling periods, there is the distinct possibility that the reciproconductive circuit will be triggered to the marking condition and there remain. This disadvantage can be readily avoided by rectifying the input signal, applying the rectified signal to a resistance-capacitance circuit of time constant long with respect to the maximum expected spacing between signal elements and, thereafter to a pulse amplifier tube which is so coupled to the reciproconductive circuit to restore it to the spacing condition.

A preferred arrangement avoiding this difficulty is shown in Fig. 10, wherein a pair of electron discharge devices 83 and 85 are connected in a differential amplifier circuit 87. The grid of the tube 83 is connected to the arm 91 of a potentiometer 93 which serves as the series connected resistors R1 and R2 of the basic circuit. A semi-conductor type rectifier 61' is shown replacing the diode previously shown. The germanium crystal diode has been used in this circuit with excellent results.

The bias battery 81 and potentiometer 97 shown provide sufficient bias voltage to give initial unbalance of the differential circuit 87 in the absence of signal. When a signal of sufficient strength to cause operation of the diode 61' appears, the unbalance disappears in so far as the response to a keyed signal is concerned. In this manner "squelch action" in the absence of a signal is provided while giving proper action when a signal is present without unduly complicating the circuit. A change of symmetry of the circuits without disturbing the balance is obtained by providing the potentiometers 93 and 97 with identical tapers and ganging them for simultaneous adjustment. Direct output is obtained from the anode of the tube 85. If desired an indirect or inverted signal train may be taken from the anode of the other tube 83. When deriving the output signal from the tube 83, a constant current tube circuit is preferably used for the cathode impedance element instead of the resistor 89 where the mark-space cross-over voltage is close to the negative limit of amplitude variation.

In Fig. 11 there is shown an arrangement used in connection with an existing electro-mechanical multiplex receiving installation where the signal is transmitted as an on-off tone signal with a tone signal demodulator 101 at the load end of the transmission line. The same basic circuit of the invention follows the demodulator 101 and a smoothing filter comprising an inductor 103 and a capacitor 105 is interposed in the circuit. No change in the theory of operation is involved provided the varying attenuation characteristics of the transmission line are considered to react on the output power of the demodulator in the same manner as if the demodulator power were constant and a similar attenuator were inserted in the transmission line between the demodulator and the conversion circuit.

A potentiometer 109 in the input circuit is used to adjust the signal level to obtain optimum results from the conversion circuit and the differential amplifier 111. Two outputs are derived for use in the multiplex apparatus. The first is a signal output amplified by a triode vacuum tube 115 for application to the message handling device and the other is a "correction voltage" obtained at the anode of another amplifier tube 119 for applica-

tion to an automatic phasing circuit in which a locally generated signal is automatically adjusted in phase relationship to the incoming signal. The amplifier tube 119 acts as an isolation device to prevent any voltage changes in the phase adjusting circuitry from adversely affecting the signal voltage obtained at the signal amplifier tube 115.

The differential amplifier 111 is so connected that the mark-space crossover voltage lies substantially midway of the normal signal limits. Any large overshoot in signal amplitude will then have no effect on the operation of the circuit and no constant current tube circuit is necessary. In either of the arrangements shown in Figs. 10 and 11, a marginal current relay may be used without any constant current tube circuitry.

In order to determine the proper setting of the level potentiometer 109, a signal level monitor circuit 121 is provided. The monitor circuit 121 comprises a pair of electron discharge structures 123-124 each having a neon indicator lamp 127, 128 in the anode-cathode path of the tube. A semi-conductor rectifier 131 and filter comprising a resistor 133 and a capacitor 135 apply a direct voltage proportional to the peak signal level to the grid of the signal voltage tube 123. The monitor circuit 121 is a differential amplifier so designed that a fixed reference voltage derived by means of resistors 151 and 152 is applied to the grid of the reference tube 124. The peak signal voltage applied to the signal tube is then compared to the reference voltage. The cathode resistors 157-159 are so chosen that a change of approximately 6 db in signal level is required for complete transfer of current from one of tubes 123-124 to the other. Hence when the signal level is within ± 3 db of the desired level both neon lamps 127 and 128 will glow. The cathode follower action of tubes 123 and 124 renders the variation between individual neon lamps of commercial availability of substantially no importance. If the level is too high only the neon lamp 127 will glow. If the level is too low only the neon lamp 128 will glow. When the signal level is between the desired limits both lamps will glow. Because the relative brightness of commercially available neon tubes is discernible to the eye, the signal level can be readily adjusted to lie very nearly midway between the levels. Thus the receiving station operator can tell at a glance whether the proper level of signal is being applied to the receiving apparatus.

An example of an adaptation of the basic circuitry according to the invention to an electronic multiplex receiver will be found in copending U. S. application Serial No. 227,344 filed May 21, 1951, of E. R. Shenk, A. E. Canfora and P. E. Volz, now Patent No. 2,716,158, granted August 23, 1955.

In an embodiment of the invention actually constructed and tested along the lines of the arrangement shown in Fig. 11, the following component parts values were employed.

The invention claimed is:

1. In a telegraph signalling circuit arrangement having a resistive circuit component across which a neutral mark-space signal appears, a capacitor, a rectifier element and a source of bias potential connected in series across said resistive circuit component, and a pair of resistance elements connected in series across said capacitor thereby to produce a polar mark-space telegraph signal between the junction of said resistance elements and a point intermediate the terminals of said source of bias potential.

2. In a telegraph signalling circuit arrangement having a resistive circuit component across which a neutral mark-space signal appears, a capacitor, a rectifier element and first and second sources of bias potential connected in series across said resistive circuit component, and a resistor connected across said capacitor and having a variable tapping thereon, thereby to produce a polar mark-space telegraph signal between the tapping of said resistor and the junction between said sources of bias potential.

3. In a telegraph signalling circuit arrangement having a resistive circuit component across which a neutral mark-space signal appears, a capacitor, a rectifier and a source of bias potential connected in series across said resistive circuit component, a potentiometer connected across said capacitor, and another potentiometer connected across said source of bias potential thereby to produce a polar mark-space telegraph signal between the arms of said potentiometers, and a differential amplifier circuit including two electron discharge systems having anodes, grids individually connected to the arms of said potentiometers and cathodes connected in common, and individual anode resistors connected to said anodes, the arms of said potentiometers being ganged to permit changing the symmetry of said circuit substantially without changing the balance thereof.

4. A circuit arrangement for converting an input signal having excursions of one polarity with respect to a reference value, to an output signal having excursions of both polarities with respect to a reference value, comprising, input terminals and output terminals, a direct current impedance element connected across said input terminals and across which said input signal appears, a

series circuit including a capacitor, a unilateral impedance device and a source of direct current potential, said series circuit being connected across said input terminals, a direct current voltage divider connected across said capacitor, a connection from an intermediate point on said voltage divider to one of said output terminals, and a connection from a point on said source of direct current potential to the other of said output terminals.

5. A circuit arrangement for converting an input signal having excursions of one polarity with respect to a reference value, to an output signal having excursions of both polarities with respect to a reference value, comprising, input terminals and output terminals, a direct current impedance element connected across said input terminals and across which said input signal appears, a series circuit including a capacitor, a unilateral impedance device and a source of direct current potential, said series circuit being connected across said input terminals, a direct current voltage divider connected across said capacitor, a connection from an intermediate point on said voltage divider to one of said output terminals, and a connection from a point on said source of direct current potential to the other of said output terminals.

6. A circuit arrangement for converting an input signal having excursions of one polarity with respect to a reference value, to an output signal having excursions of both polarities with respect to a reference value, comprising, input terminals and output terminals, a direct current impedance element connected across said input terminals and across which said input signal appears, a series circuit including a capacitor, a unilateral impedance device and a source of direct current potential, said series circuit being connected across said input terminals, a direct current voltage divider connected across said capacitor, a connection from an intermediate point on said voltage divider to one of said output terminals, and a connection from the junction between said unilateral impedance device and said source of direct current potential to the other of said output terminals.

7. A circuit arrangement for converting an input signal having excursions of one polarity with respect to a reference value, to an output signal having excursions of both polarities with respect to a reference value, comprising, input terminals and output terminals, a direct current impedance element connected across said input terminals and across which said input signal appears, a series circuit including a capacitor, a unilateral impedance device and a source of direct current potential, said series circuit being connected across said input terminals, a direct current voltage divider connected across said capacitor, a connection from an intermediate point on said voltage divider to one of said output terminals, and a connection from the end of said source of direct current potential connected to one of said input terminals to the other of said output terminals.

8. In a telegraph signalling circuit arrangement having a resistive circuit component across which a neutral mark-space signal appears, a capacitor, a rectifier and a source of bias potential connected in series across said resistive circuit component, a potentiometer connected across said capacitor, and another potentiometer connected across said source of bias potential, and output terminals connected respectively to said potentiometers, whereby to provide a polar mark-space telegraph signal at said output terminals.
